UNITED STATES PATENT OFFICE

HENRY G. SWEITZER, OF DETROIT, MICHIGAN

RADIATOR WALL SHIELD

Application filed March 7, 1927. Serial No. 173,498.

The invention relates to radiator shields and more particularly to improvements in radiator wall shields of the type used on standard radiators in heating systems such as 5 steam, vapor or hot water.

The invention has among its objects the production of an improved simple and efficient radiator shield designed to secure a better circulation and a more uniform distribution of the heat. A further feature of the invention resides in the provision of means for increasing to a desired degree the humidity of the air in the room heated. A further object is the provision of a shield which is 10 merely slipped over the top of the radiator and has no positive connection therewith, thus reducing the cost of installation an appreciable amount. A further feature is to provide an air filter so designed as to purify 15 the heated air and to be readily applied to and removed from the radiator shield and which does not materially retard the circulation of the heated air. Other objects, advantages and features of construction will be 20 made more apparent as this description proceeds, especially when considered in connection with the accompanying drawings, wherein,

Figure 1 is a perspective view of a radiator 30 to which is attached a radiator shield embodying my invention;

Figure 2 is a cross section taken on the line 2—2 of Figure 1;

Figure 3 is a sectional view taken on the 35 line 3—3 of Figure 1;

Figure 4 is a sectional view of a modified form of construction.

Referring now to the drawings wherein like characters of reference designate corresponding parts throughout the several views, the numeral 1 indicates a standard radiator of the type used in hot water, steam or vapor heating systems and 2 indicates a wall to which said radiator is adjacent. The improved shield is superposed on the radiator and includes a top member 3 spaced from the radiator and having front and rear members 4 and 5 formed integral with and extending downwardly from the top member 3. The rear member 5 as shown in Figure 2

of the drawings is spaced from the radiator a suitable distance and is preferably formed with an open return-bent portion 6 at the lower edge thereof adapted to detachably receive the open return-bent portion 7 formed 55 at the upper edge of the apron 8. This arrangement not only prevents discoloration of the wall adjacent the radiator but also serves to deflect the hot air currents outwardly into the room. The front member 4 60 is somewhat similar to the back member 5 and is spaced from the radiator a sufficient distance to receive the filter pad 9. This pad is preferably formed of metal fiber, such as steel wool and as shown in Figure 5 is 65 inclosed in a wire screen 10, which rests on the open return-bent portion 11 formed at the lower edge of the front piece 4. The front piece is further provided with a plurality of die stamped openings 12 permitting 70 the air currents to escape from the interior of the shield. The filtering pad may be readily removed from the shield by merely exerting a slight inward pressure upon the lower edge thereof thus forcing the pad inward toward the radiator and enabling the pad to pass through the clearance between the return-bent portion and the radiator. 75

Extending longitudinally of the shield and interposed between the top member 3 and the radiator are the tubes 13 and 14 secured to the top piece upon opposite sides thereof. The tube 13 and top member are provided with the aligned openings 15 through which a suitable liquid such as water may be poured. 80 With this arrangement as the air becomes heated, the water will vaporize and pass through the openings aforesaid into the room rendering the air in the room humid and agreeable. Superposed upon the top of the 85 radiator and conforming in shape thereto is a second top piece 17 spaced below the top member 3 and having the opposite sides thereof secured to the tubes 13 and 14. The second top piece 17 preferably extends the 90 full length of the shield and forms therewith an air chamber 18 in which the temperature is somewhat modified so that various articles 95 may be placed on top of the shield without material danger. For closing the ends of 100

the shield as well as the ends of the tubes 13 and 14, I provide the inter-changeable end pieces 19 secured to the opposite ends of the shield by any suitable means such as spot welding and formed with a plurality of openings 20 opposite the air chamber 18 permitting circulation of air through this chamber. In order to adapt the shield for various kinds of heating systems the end pieces are cut away as indicated at 21 affording clearance for a return pipe or valve.

In the modification illustrated in Figure 4 I have shown a radiator shield designed to be used as a seat. For accomplishing this result I provide a corrugated member 22 made of heavy sheet metal and positioned within the air chamber 18. This member preferably extends the full length of the chamber and is secured to the tubes 13 and 14 and the end pieces by spot welding. With this particular construction the air chamber is especially desirable not only from the standpoint of rigidity due to the corrugated member 22, but also by reason of the fact that the ventilated air chamber insulates the top member 3 from excessive heat thus rendering the same desirable as a seat.

Thus from the foregoing it will be noted that the herein described arrangement renders possible the production of a commercially satisfactory radiator shield that is relatively simple in construction owing to the minimum number of parts employed and one that is relatively inexpensive to manufacture.

35 What I claim as my invention is:

1. A device of the class described including in combination, a shield adapted to seat upon a radiator and having openings therein for the passage of air, and means for screening the air passing through said openings including a pad of steel wool positioned upon said shield.

2. A device of the class described including in combination, a shield having a top portion adapted to seat upon a radiator and having an apertured front wall extending downwardly from the said top portion and spaced outwardly from the front side of the radiator and a filtering element removably supported upon said wall adjacent the apertures, said wall being adapted to be spaced sufficiently from the radiator to permit the insertion and removal of the filtering element without detachment of said shield from the radiator.

55 3. A device of the class described including in combination, a shield having a top portion adapted to seat upon a radiator and having an apertured depending front wall spaced outwardly from the radiator and terminating in an inwardly extending flange, and a flat filtering element supported upon said flange against the apertured portion of the front wall.

4. A device of the class described, including in combination a shield adapted to seat

upon a radiator, one wall of said shield terminating in an inturned flange and having a series of openings therein for the passage of air, and a filtering element removably supported upon said flange adjacent the apertures, the inner longitudinal edge of said flange terminating a sufficient distance from the adjacent side of the radiator to permit removal of the filtering element without detaching the shield from the radiator.

5. A device of the class described including in combination, a metal shield adapted to seat upon a radiator and having openings therein for the passage of air, and filtering means for screening the air including a pad of steel wool positioned upon said shield and cooperating therewith to provide an all-metal construction constituting a heat conducting filter whereby reduction of the heating efficiency of the shield is prevented.

In testimony whereof I affix my signature.
HENRY G. SWEITZER.
